UNITED STATES PATENT OFFICE.

ALBERT E. BARBER, OF CHICAGO, ILLINOIS.

ELECTRIC LANTERN.

Application filed November 5, 1923. Serial No. 672,902.

To all whom it may concern:

Be it known that I, ALBERT E. BARBER, a citizen of the United States, and a resident of Chicago, in the county of Cook and State 5 of Illinois, have invented a new and useful Improvement in Electric Lanterns, of which the following is a full, clear, and exact description.

My invention relates to improvements in 10 electric lanterns, and it consists in the combinations, constructions, and arrangements herein described and claimed.

An object of my invention is to provide 15 an electric lantern which is especially adapted for trainmen, in that it is compact in structure and is provided with a supporting standard and a relatively large rigid handle, whereby the device may be readily disposed upon a supporting surface or easily manipulated by a trainman in giving his 20 signals.

A further object of my invention is to provide a device of the type described which has a novel switch and electrical connections 25 between the switch and the light.

A further object of my invention is to provide a device of the type described which has means for holding additional light bulbs.

Other objects and advantages will appear 30 in the following specification, and the novel features of the invention will be particularly pointed out in the appended claims.

My invention is illustrated in the accompanying drawings forming part of this application, in which—

Figure 1 is a side elevation of the device,

Figure 2 is a bottom plan view of the device,

Figure 3 is a vertical section through the device,

Figure 4 is a section along the line 4—4 of Figure 3, and

Figure 5 is a plan view of the interior 45 of the cover.

In carrying out my invention I provide a cylindrical casing 1 that has a concave bottom 2 that acts as a reflector for a light 3. The casing 1 is adapted to be supported 50 by a frame 4. It will be noted from Figures 1 and 2 that the frame 4 consists of a rectangular base 5 and supporting legs 6

that are secured to the base and to the casing 1.

The casing is adapted to be carried by a 55 handle 7. The handle consists of a rubber or fiber tubing 8 that is disposed over a metal tubing 9. The ends of the handle are inserted into sockets 10 that in turn are secured to a casing 1 by means of rivets 11. 60 Rivets 12 connect the tubings 8 and 9 to the socket 10. The trainman in using this device grasps the handle 7 and swings the device in the customary manner. The handle is rigidly secured to the casing 1 so that 65 the device may be readily swung by the person using the device.

In Figures 3 and 4 I have shown the novel means by which the light is energized. 70 The light 3 is received in a socket 12, this socket being provided with an exteriorly threaded portion 13 that is adapted to receive a nut 14. The portion 13 provides a shoulder 15 at the point where the portion 13 merges into the socket 12. The portion 75 13 is adapted to project through an opening 16 in the reflector 2. The nut 14 locks the socket 12 to the reflector 2. It will be noted that the portion 13 takes the place of the standard light socket, and is much thicker 80 than the walls of the standard light sockets. The life of this socket will therefore be much longer. This is a vital feature of the device, since lights have to be removed and inserted a great number of times as they 85 become worn or broken.

An insulating disc 17 is disposed upon the inner surface of the socket 12 and is held in place by means of a rivet 18. It 90 will be noted that the rivet is insulated from the socket 12 by means of a fiber washer 19. The rivet 18 also secures a conductor disc 20 to the disc 17. A conductor ring 21 is disposed concentrically around the disc 20 and secured by rivets 22. An electrical conducting strip 23 is connected to the ring 21 by a rivet 24, and is connected to the casing 1 by means of rivet 25. The strip 23 is insulated from the casing by means of an insulating strip 26. The rivet 25 extends 95 through an opening 27 in the casing and is spaced from the walls of the opening (see Figure 4). A fiber disc 28 is disposed in the outer side of the casing 1 and has a por-

tion 29 that extends into the opening 27 so as to insulate the pin 25 from the casing 1. A spring contact member 30 is secured to the conducting strip 23 by means of a rivet 25. It will be noted that the contact 30 has a curved portion 31 for a purpose herein-after described.

The contact 30 forms one of the terminals in a switch indicated generally at 32. The 10 switch comprises a casing 33 that is secured to the casing 1 and which slidably carries a pin 34. A fiber sleeve 35 is disposed on the pin 34 and abuts a shoulder 36 on the pin. A metal sleeve 37 is also 15 mounted upon the pin 34 and abuts the sleeve 35. It will be noted that the sleeve 35 is conical-shaped and that a portion of the sleeve 37 is also conical-shaped. The 20 largest diameters of these conical-shaped portions are disposed adjacent to each other for a purpose now to be described. In Figure 4 the switch is shown in the position of making a contact between the spring contact member 30 and the sleeve 37. The 25 tension of the spring contact member 30 is sufficient to normally keep the pin 34 in the position shown. When it is desired to open the switch, it is merely necessary to move the pin 34 so as to cause the 30 rounded portion 31 of the spring contact 30 to ride up and over the conical portion of the sleeve 37 and on to the conical portion of the insulating sleeve 35. As heretofore stated, the slope of the sleeve 35 35 tends to continue to move the pin 34 in the same direction. In this manner, the switch 32 acts as a snap switch, i. e., it is 40 yieldingly held in open or closed position.

The casing 1 is adapted to hold a battery 38 that has terminals 39 and 40. These terminals yieldingly contact with the conductor disc 20 and ring 21 respectively. It will be seen from this construction that the terminals 39 and 40 will always 45 contact with the disc 20 and the ring 21 no matter in what position the battery 38 is disposed with respect to the casing 1.

The terminals 39 and 40 are yieldingly held in engagement with the disc 20 and 50 ring 21 by means of a spring 41 that is disposed in the interior of the cover 42. The cover 42 is in turn locked to the casing 1 by means of spring pressed pins 43. The pins 43 are carried by the leaf springs 55 44 that in turn are secured to the casing 1. The pins 45 are also carried by the springs 44 and project through openings 46 in the

casing 1. By manually pressing the pins 45 the pins 43 may be moved so as to permit the cover 42 to be removed from 60 the casing 1.

The cover 42 also has a light carrying member 43' that is provided with two cylindrical portions 44' in which lights 45' may be disposed.

From the foregoing description of the various parts of the device, the operation thereof may be readily understood. When using the device, it is merely necessary to insert the battery into the casing, the terminals automatically being placed in electrical connection with the light 3 and the switch 32 as soon as the battery is disposed in place. When the switch is closed, the current will flow from the terminal 40 75 of the battery to the ring 21 and then through the strip 23 to the rivet 25, contact 30, sleeve 37, casing 33, casing 1, socket 12, to the light 3. The current from the light will flow through the rivet 18, the disc 20, 80 and back to the terminal 39 of the battery 38.

The device is very compact in construction and may be more conveniently used than the standard trainmen's lights. The 85 spring 41 keeps the terminals 39 and 40 in contact with the disc 20 and ring 21 no matter in what position the lantern is swung. The casing is provided with reenforcing ribs 46' and 47 that also aid in 90 beautifying the device. The rib 47 also provides a stop for the cover 42, whereby the cover is automatically aligned with the pins 43.

I claim:

1. An electric lantern comprising a casing having an opening therein, a socket having a reduced threaded portion disposed in said opening, a locking nut adapted to be screwed onto the reduced threaded portion 100 and to lock the socket to the casing, an insulating disc carried by said socket and adapted to support a battery, and spring means for holding said battery in place.

2. An electric lantern comprising a casing adapted to carry the battery for a flash light, a cover removably secured to said casing, a strip fashioned into two light receiving loops, a leaf spring for holding the battery in place, and means for securing said strip and said leaf spring to said cover.

ALBERT E. BARBER.
